UNITED STATES PATENT OFFICE.

CHARLES H. SAWYER, OF MINNEAPOLIS, MINNESOTA.

MOP.

SPECIFICATION forming part of Letters Patent No. 371,633, dated October 18, 1887.

Application filed January 6, 1887. Serial No. 223,540. (No model.)

To all whom it may concern:

Be it known that I, CHARLES H. SAWYER, of Minneapolis, in the county of Hennepin and State of Minnesota, have invented certain new and useful Improvements in Mops, of which the following is a specification.

My invention relates to an improvement in mops for cleansing floors; and the object I have in view is to provide this class of utensils with an improved attachment whereby the cloth may be wrung without bringing the hands in contact with it.

My invention consists, generally, in the combination and arrangement hereinafter described, and particularly pointed out in the claims.

In the drawings which form part of this specification, Figure 1 is a side elevation of my improvement, showing it attached to the mop-handle in the position when not in use. Fig. 2 is a similar view showing it in position ready for operation. Fig. 3 is a plan view of Fig. 2. Fig. 4 is a plan view illustrating the method of operation. Figs. 5, 6, 7, and 8 are details.

In the drawings, 2 represents the handle of an ordinary mop, having a clamp, 4, at its lower extremity, to which the cloth or mop 6 is attached.

8 represents a loose sleeve or socket which encircles the handle 2 and slides freely thereon.

10 is a bracket fast to the sleeve 8 and projecting downward from it. In the lower extremity of this bracket one end of the hollow shaft

35 12 is fixed. The opposite end of this shaft is attached to the jaw 14. A shaft, 16, extends through the shaft 12, and its forward end is attached to the jaw 18 and the rear end to the lever 20. The lever 20 extends upward and is provided with a pawl or latch, 22, which is arranged to catch over a suitable projection, 23, on the sleeve 8, to hold the jaws 14 and 18

45 in an open position, as shown in Fig. 5. Any other suitable means may be used in place of the latch for holding the lever in position.

The sleeve 8 is preferably provided with a rubber ring or band, 24, which extends around it. An opening is made through the sleeve upon each side under the band 24. This allows the 50 band to come in contact with the handle. As the band is secured to the sleeve and also strikes the handle, it will cause sufficient fric-

tion to hold the sleeve in place upon the handle and prevent it from sliding by its own weight as the mop is used.

26 is a collar held upon the handle by a set-screw, 28. This collar may be placed in any required position upon the handle to limit the forward movement of the sleeve.

30 is a bell-crank lever or trip fulcrumed upon the sleeve, one arm extending in front of the sleeve and the other arm projecting under the pawl 22 as the sleeve 8 is thrown forward. The arm of the lever 30 comes in contact with the collar 26 and is forced back and 60 raises the outer arm, and with it the pawl 22. This movement releases the side pawl from the catch or projection upon the sleeve 8 and releases the lever 20. A coil-spring, 32, is attached to the lever 20 and to the bracket 10. 70 The tension of this spring throws down the lever 20 after it is released from the sleeve, partially revolves the shaft 16, and brings the jaw 18 into position to grasp the cloth of the mop, as shown in Figs. 4 and 6.

75 The operation is as follows: When it is desired to wring the cloth, the sleeve is forced forward upon the handle until the collar is reached. When this position is attained, the jaws 14 and 18 will be near the front end of 80 the cloth. The trip 30 is operated, which throws out the pawl and releases the lever 20. The shaft 16 is revolved and the jaws grasp the cloth. The handle 2 is now revolved and the cloth twisted until it is sufficiently 85 freed from water.

The form of jaws which I prefer to use is substantially as shown in Figs. 5 and 6. It will be seen that the projections or teeth upon the jaw 14 curve in the opposite direction 90 when the two clamps are together, as seen in Fig. 6, which causes the twist of the cloth to draw the two clamps closer together and relieve the spring.

The teeth on the jaws are slanted backward 95 to allow them to pass under the cloth as the clamp is forced down without catching in the cloth.

I claim as my invention—

1. The combination, with the mop, of the 100 sleeve 8, having the bracket 10, the shaft 12, secured to said bracket, the jaw 14, secured to said shaft, the shaft 16, and the jaw 18, secured to said shaft 16, all substantially as described.

2. The combination, with the mop, of the sliding sleeve upon the handle of said mop, the shafts 12 and 16, supported by said sleeve, the clamping-jaws, and means, as described, 5 for operating said jaws, all substantially as described.

3. The combination, with the mop, of the sliding sleeve 8, arranged upon the mop-handle, the bracket 10, supported upon said sleeve, 10 the clamping-jaws 14 and 18, carried by said bracket, the shafts 12 and 16, and means, as described, for operating said jaws, all substantially as described.

4. The combination, with the mop, of the sliding sleeve 8, having the bracket 10 secured thereto, the shafts 12 and 16, carrying, re- 15

spectively, the clamping-jaws 14 and 18, the lever 20, secured to said shaft 16 and provided with the pawl 22, the spring 32, and catch 23, all substantially as described. 20

5. The combination, with the mop, of the sliding sleeve upon the handle of said mop, the shafts 12 and 16, and the clamping-jaws having teeth extending in opposite directions, for the purpose set forth. 25

In testimony whereof I have hereunto set my hand this 3d day of January, 1887.

CHARLES H. SAWYER.

In presence of--

A. C. PAUL,

R. H. SANFORD..
